UNITED STATES PATENT OFFICE.

GEORGE P. BOSWORTH, OF CENTRAL FALLS, RHODE ISLAND, ASSIGNOR TO HEMPHILL COMPANY, OF PAWTUCKET, RHODE ISLAND, A CORPORATION OF MASSACHUSETTS.

KNITTING MACHINE.

Application filed October 22, 1919, Serial No. 332,449. Renewed September 9, 1922. Serial No. 597,230.

To all whom it may concern:

Be it known that I, GEORGE P. BOSWORTH, a citizen of the United States, residing at Central Falls, in the county of Providence, State of Rhode Island, have invented a certain new and useful Improvement in Knitting Machines, of which the following is a specification, reference being had therein to the accompanying drawings.

10 The invention consists in knitting mechanism of novel character adapted to operate with reciprocating knitting strokes to produce by flat knitting a broad selvaged web having joined therewith a group of narrow strips. The said mechanism comprises as its more essential elements knitting-cams by which the needles are actuated to knit, needles having in connection therewith selective butts which are grouped for strip production, means for retiring the needles from operative relations with the knitting-cams prior to selection for each strip, group-selective cams arranged for engagement with corresponding groups of selective butts to 15 select the needle-groups required for knitting successive narrow strips, and needle-restoring means for returning to operative relations with the knitting-cams needles that have been placed out of such relations.

20 The invention is shown in the drawings as illustratively embodied in a machine of the same general construction as the well-known Banner machine, with additions and changes for the purposes of the invention.

25 The principles and general construction of the Banner machine are substantially set forth in U. S. Letters Patent to J. D. Hemphill, No. 933,443, granted Sept. 7, 1909.

In the drawings,—

30 Fig. 1 shows in side elevation sufficient of the said machine, including the illustrative embodiment of the invention, to render clear the relations, mode of operation, etc., of the parts involved in the invention.

35 Fig. 2 is a front elevation thereof.

40 Fig. 3 is a diagram of the needle-system and novel cam-system comprised in the said embodiment.

45 Fig. 4 shows combined needles and jacks illustrating the different arrangements of selective butts.

50 Figs. 5 and 6 show modified forms of the needles and jacks.

Fig. 7 is a side elevation of the system of group-selective cams and certain of the adjacent parts. 55

Fig. 8 is an elevation thereof looking at the working ends of said cams.

Fig. 9 is an elevation thereof, looking at the same from in front of the machine. 60

Fig. 10 is a plan view thereof.

Fig. 11 is a side elevation of one of the operating bell-cranks for the group-selective cams, and Fig. 12 is an end view of such bell-cranks. 65

Fig. 13 is a side elevation and Fig. 14 a plan view of one of the operating cam-bars for the group-selective cams.

Fig. 15 is a side elevation of one of the group-selective cams, Fig. 16 an elevation looking at the working end thereof, Fig. 17 a plan view, and Fig. 18 an elevation of the side opposite that shown in Fig. 15. 70

Figs. 19 and 20 are views of a glove-unit on the order of that which may be produced by a machine embodying the invention, looking at opposite sides of the same. 75

In the drawings, the machine-frame is marked *a*. The rotatable needle-cylinder is marked *N*. The non-rotatable cam-carrier is marked *H*, the annular ledge adjoining said cam-carrier being marked *M*. The knitting or stitch-cams are mounted in connection with the cam-block *D*, Fig. 2. The parts by which the needle-cylinder is reciprocated are shown in Fig. 1. They comprise the bevel-gear-wheel *n'* meshing with a like bevel-gear-wheel (not shown) connected with the needle-cylinder, a spur-pinion *i''* in clutch-connection with the shaft *s* on which the bevel-gear-wheel *n'* is fixed, a toothed sector *i⁵* meshing with the spur-pinion, and the rotating gear-wheel *i'* having a crank-pin connected by a pitman or connecting-rod *i²* to the said sector and serving through such connection to vibrate the sector so as to impart the required reciprocating movement to the needle-cylinder through the described gearing. At *g*, Figs. 1 and 2, is a pattern-drum upon the pattern-shaft of the machine, such pattern-drum being employed for controlling the working of the various special cams to which reference has been made. 80

85 Fig. 4 shows combined needles and jacks illustrating the different arrangements of selective butts.

90 Fig. 5 is a diagram of the needle-system and novel cam-system comprised in the said embodiment.

95 Fig. 6 shows modified forms of the needles and jacks.

100 The Banner machine is constructed in practice with a train of gearing (not shown) 105

for imparting also a continuous rotation in one direction to the needle-cylinder, as well as with a clutch-mechanism under the control of pattern-devices located at the point

- 5 f^* in Fig. 2, whereby for tubular knitting driving relations may be established between the said train of gearing and the needle-cylinder, while for reciprocating knitting the said train may be disconnected from 10 the said cylinder and the train for imparting reciprocating movement to the cylinder may be connected with the latter.

The needles 1 have in connection therewith knitting-butts 1^a which are engaged by 15 the knitting-cams to cause them to knit, and the other butts, hereinafter termed selective butts, which are provided for cooperation with the group-selective cams.

The means for placing the needles out of 20 operative relations with the knitting-cams, prior to selection of the group of needles on which a narrow strip is to be knit, may vary in practice. Herein such means consists of a withdrawal cam 2, shown best in Figs. 2 25 and 3, which, when brought into action as in Fig. 1 acts upwardly against the knitting-butts of all the needles to raise the latter relative to the knitting-cams, to thereby place the knitting-butts out of the way of 30 the knitting-cams. Normally the withdrawal cam 2 occupies an outwardly retracted position, away from the periphery of the needle-cylinder, in which it will not act upon the knitting-butts.

35 The group-selective cams are shown at 3, 4, 5, 6, 7. See Figs. 7 to 18. The selective butts with which such cams engage are represented at 3^a, 4^a, 5^a, 6^a, and 7^a, Figs. 3 and 4. The groups of selective butts are arranged at different levels, and the group-selective cams are disposed at corresponding levels, one above another. Normally, these cams occupy outwardly-retracted, inoperative, positions.

40 The needle-restoring cam is shown at 8, it being arranged for engagement with the knitting-butts 1^a to depress the elevated and inoperative needles so that their knitting-butts may be disposed in position to be engaged by the knitting-cams. Normally, this cam occupies a position close to the periphery of the needle-cylinder.

45 The machine is adapted for the production of the glove-unit or blank that is shown 55 in Figs. 19 and 20, comprising a flat selvaged wrist-portion x , a thumb-strip x' that is doubled upon itself and united by its opposite ends with the said unit or blank at opposite sides of a transverse slit formed in 60 the latter, a flat selvaged palm-portion x^2 , four finger-strips x^3 , x^4 , x^5 , x^6 , of suitable length to form glove-fingers when doubled back upon themselves, and a portion x^7 suitable for the back of the hand and wrist 65 of a glove. The strips for the second, third,

and little fingers are knit with widenings y , y' , and y^2 , respectively, under-lapping the adjoining finger-strips, and constituting gussets.

In the operation of the machine, the wrist-portion x is knit of its full width by reciprocating motion of the needle-cylinder, all of the needles of the series required to produce such width being in operation. On arrival at the point in the length of such portion at which the thumb-strip x' springs therefrom, the restoring-cam 8 being given its outwardly-retracted inoperative position, the withdrawal-cam 2 is caused to move inward into position to engage with the knitting-butts 1^a, and it raises all of the needles of the said series to the inoperative level so as to place their knitting-butts in inoperative relations with respect to the knitting-cams. Following such action, the cam 2 is 85 retired outward. Selective cam 3 is caused to move inward into position to act upon the tops of the selective butts 3^a, these belonging to the needles intended to be used in knitting the thumb-strip, x' , and it depresses such needles to the working level so as to lower their knitting butts into position to be engaged by the knitting-cams. Selective cam 3 then is retired outward. Continuance of the reciprocating knitting produces 95 the thumb-strip x' . As soon as the latter has been knit of the required length, the needle-restoring cam 8 is caused to move inward into operative position to act upon the knitting-butts of the needles occupying a 100 raised inoperative position, and it depresses such needles to the working level. Then the wide flat selvaged palm-portion x^2 is knit, the final portion of the thumb-strip becoming joined to the said palm-portion, 105 On completion of the palm-portion, the withdrawal cam 2 is moved inward into position to engage the knitting-butts so as to raise to the inoperative level the needles which were used in knitting the palm-portion, and selective cam 4 is moved inward to 110 engage with selective butts 4^a of the needles for the little-finger strip. Thereby the said needles are moved down to the working level and placed in operative relations with the 115 knitting-cams. The little-finger strip is knit of the required length and then the withdrawal cam 2 is called into action to raise to the inoperative level the needles used in knitting such strip, following which the selective cam 5 is called into action to engage 120 with selective butts 5^a to move down to the working level the needles required for knitting the third-finger strip. Some of the selective butts 5^a are upon needles which 125 were used in knitting the little-finger strip, so that such needles are brought into action again for knitting the third-finger strip, for the purpose of forming the gusset y and making the third-finger strip broader. On 130

completion of the third-finger strip, the withdrawal cam 2 is called into operation and raises to the inoperative level the needles used in knitting such strip, and selective 5 cam 6 is called into action and engages the selective butts 6^a to move down to the working level the needles required for knitting the second-finger strip. Some of the selective butts 6^a are upon needles which were 10 used in knitting the third-finger strip so that such needles are brought into action again in knitting the second-finger strip, for the purpose of forming the gusset y¹ and making such strip broader. On completion 15 of the second-finger strip the withdrawal cam 2 is called into operation and raises to the inoperative level the needles used in knitting such strip, and selective cam 7 is called into action and engages with 20 selective butts 7^a to move down to the working level the needles required for knitting the first-finger strip. Some of the selective butts 7^a are upon needles which were used in knitting the second-finger strip, so that 25 such needles are brought into action again in knitting the first-finger strip for the purpose of forming the gusset y² and making such strip broader. After knitting the first-finger strip of the required length, the needle-restoring cam 8 is brought into action 30 to lower all the needles to the operative level, and knitting proceeds upon all the needles to form the broad flat selvaged web x⁷ for the back of the hand and wrist.

Usually the operation of the machine proceeds so as to produce a succession of glove-blanks or units in string-form, the knitting of portion x⁷ of one blank or unit being continued to produce the wrist-portion x of 35 the next succeeding blank or unit, and so on.

In some instances, lengths of tubular work produced by round and round knitting may be alternated with the flat work produced in the manner just described.

The manner and means of placing the withdrawal cam 2, the restoring cam 8, and the group-selective cams 3, 4, 5, 6, and 7 in their respective operative and inoperative 45 positions under the control of pattern-indicators upon pattern-drum g may vary in practice. Herein the cams 2 and 8 are furnished with stems 2^m, 8^m, Fig. 1, mounted in guides in stands 2ⁿ, 8ⁿ, upon the machine-frame, so that the said cams are capable of 50 being moved radially toward and from the periphery of the needle-cylinder. Pins 2°, 8°, rising from said stems are engaged by the outer ends of contracting spiral springs 2^p, 8^p, tending to draw the said cams inward toward 55 the working positions of the cams. The group-selective cams 3, 4, 5, 6, and 7, respectively are furnished (Figs. 7 to 18) with stems 3^m, 4^m, 5^m, 6^m, and 7^m mounted in guides in a stand 3ⁿ upon the machine-frame, so that 60 such cams also have capacity to move radi-

ally. Pins 3°, etc., projecting horizontally from said stems through slots in one side-wall of stand 3ⁿ are engaged by contracting spiral springs 3^p, etc., tending to draw the respective group-selective cams inward toward their working positions. The employment of springs to act with yielding force to move these various cams inward, when such movement is permitted by the pattern-indicators of drum g, avoids injury from strain 70 or breakage in case a cam should encounter a needle-butts and be arrested thereby in its movement inward.

Under the control of the pattern-indicators of drum g, the needle-withdrawal cam 2 is moved outward into its inoperative position, clear of the needle-butts 1^a, by means of a bell-crank 2^r, connecting-rod 2^s, and pattern-lever 2^t, and contracting spiral spring 2^u. The said bell-crank is pivotally mounted 80 upon one side-wall of stand 2ⁿ with its upwardly-extending arm arranged to engage a pin 2^a projecting horizontally from stem 2^m out through an elongated slot in said side-wall, the outwardly-extending arm of said bell-crank being connected by means of the rod 2^s with the forward arm of the pattern-lever and such arm of the pattern lever being held in contact with the pattern-drum g by means of the said spring 2^u. A depression in 90 the line of pattern-indicators presented to the pattern-lever, permits the spring to actuate the pattern-lever, rod, and bell-crank to move the cam 2 outward into inoperative position, clear of the butts 1^a. An elevation in the said 100 line operates the parts reversely to swing the bell-crank inward and permit spring 2^u to move the cam 2 into working position for engagement with butts 1^a to elevate the needles above the knitting cams.

The needle-restoring cam 8 is operated from the said pattern-lever 2^t by means of a bell-crank 8^r and a rod 8^s. The said bell-crank is pivoted upon one side-wall of stand 8ⁿ and arranged to engage a pin projecting 110 laterally from stem 8^m of said cam 8. It is connected by the rod 8^s to the rearward arm of the pattern-lever, so that the position of the latter controls that of the cam 8. It will be apparent that in consequence of being 115 controlled from the opposite arms of the pattern-lever 2^t, the needle-restoring cam 8 will be caused to occupy its inward or working position when the needle-withdrawing cam 2 is caused to occupy its outward or inoperative 120 position, and vice versa.

The respective group-selective cams are given their working and inoperative positions under the control of the pattern-indicators of drum g, by means of pattern-levers 125 g', springs g² by which said pattern-levers are moved toward the periphery of the drum, rods g³ having their lower ends joined to said pattern-levers, bell-cranks 3^r, etc., pivotally mounted upon stand 3ⁿ, and cam-bars 3^t, 130

etc., connected with said bell-cranks and engaging with the stems 3^m, etc., of the group-selective cams. Each stem 3^m, etc., has a notch 3^u, Figs. 15, 17, and 18, in which the corresponding cam-bar works, and each cam-bar 3^t, etc., has an incline upon its outer side adapted to cooperate with one vertical wall of said notch. Flat surfaces 3^v and 3^x at opposite ends of incline 3^y are presented to said end-wall in the opposite extreme positions of a cam-bar. While the cam-bars occupy their right-hand positions as in Fig. 8, the flat surfaces 3^x, etc., of the respective cam-bars keep the respective group-selective cams in their outward, inoperative, positions. When a cam-bar is moved toward the left from the position in Fig. 8, the incline 3^y permits the spring, as 3^p, of the corresponding group-selective cam to move the latter inward into operative position for engagement with the corresponding group of selective butts. Movement of such cam-bar from left to right will cause its incline to draw the said group-selective cam outward into inoperative position again.

The needles employed in the machine may be combined with jacks, as in Figs. 4 and 5, with the knitting-butts 1^a upon the needles and the selective butts upon the jacks, as in Fig. 4, or with both the knitting-butts and the selective butts upon the jacks alone, as in Fig. 5. Or, instead of employing separately formed jacks, the selective butts may be formed upon extensions of the wire of which the needles are formed, as in Fig. 6.

What is claimed as the invention is:—

1. Knitting mechanism operating with reciprocating knitting strokes to produce by flat knitting a broad selvaged web having joined therewith a group of narrow strips, including knitting-cams by which the needles are actuated to knit, needles having in connection therewith selective butts grouped for strip-production, means for retiring the needles from operative relations with the knitting-cams prior to selection for each strip, group-selective cams respectively engaging with corresponding groups of selective butts to select the needle-groups required for knitting successive narrow strips, and needle-restoring means for returning to operative relations with the knitting-cams needles remaining out of such relations, for the knitting of broad web.
2. Knitting mechanism operating with reciprocating knitting strokes to produce by flat knitting a broad selvaged web having joined therewith a group of narrow strips, including knitting-cams by which the needles are actuated to knit, needles having in connection therewith selective butts grouped for strip-production, a withdrawal-cam for placing the needles out of operative relations with the knitting-cams prior to selection for each strip, group-selective cams

respectively engaging with corresponding groups of selective butts to select the needle-groups required for knitting successive narrow strips, and a needle-restoring cam for returning to operative relations with the knitting-cams needles remaining out of such relations for the knitting of broad web.

3. Knitting mechanism operating with reciprocating knitting strokes to knit a broad flat web having joined therewith a group of laterally-overlapping narrow strips, including knitting-cams by which the needles are actuated to knit, needles having in connection therewith selective butts grouped for strip-production and for overlapping gusset-formation, means for placing the needles out of operative relations with the knitting-cams prior to selection for each strip, group-selective cams respectively engaging with corresponding groups of selective butts to select the needle-groups required for knitting successive narrow strips and their gussets, and a needle-restoring cam for returning to operative relations with the knitting-cams needles remaining out of such relations, for the knitting of broad web.

4. Knitting mechanism operating with reciprocating knitting strokes to knit a broad flat web having joined therewith a group of laterally-overlapping narrow strips, including knitting-cams by which the needles are actuated to knit, needles having in connection therewith selective butts grouped for strip-production and for overlapping gusset-formation, a withdrawal cam for placing the needles out of operative relations with the knitting-cams prior to selection for each strip, group-selective cams respectively engaging with corresponding groups of selective butts to select the needle-groups required for knitting successive narrow strips and their gussets, and a needle-restoring cam for returning to operative relations with the knitting-cams needles remaining out of such relations, for the knitting of broad web.

5. In a knitting machine, in combination, a needle-withdrawal cam, a needle-restoring cam, a pattern, a pattern-lever, and means for controlling the respective cams from opposite arms, respectively, of said pattern-lever whereby one cam is caused to assume working position as the other is moved out of working position, and vice versa.

6. In a knitting machine, in combination, a needle-withdrawal cam, a needle-restoring cam, springs acting with a tendency to give said cams their working positions, bell-cranks adapted to withdraw said cams from working positions, a pattern, and a pattern-lever having one arm thereof operatively combined with one bell-crank and the other arm thereof operatively combined with another bell-crank.

7. In a knitting machine, in combination,

radially-movable needle-withdrawal and restoring cams, springs respectively acting with tendency to move the respective cams inward into working position, transversely 5 movable cam-bars respectively engaged with the respective cams, bell-cranks for moving the respective cam-bars to bring about outward movement of the cams or permit inward movement thereof under the action of the springs, and a pattern, and means intermediate the same and said bell-cranks controlling the latter.

In testimony whereof I affix my signature.

GEORGE P. BOSWORTH.
